UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WARP STOP-MOTION.

1,360,638.

Specification of Letters Patent. Patented Nov. 30, 1920.

Application filed August 5, 1918. Serial No. 248,268.

To all whom it may concern:

Be it known that I, ELBRIDGE R. HOLMES, a citizen of the United States, residing at Worcester, in the county of Worcester and State of Massachusetts, have invented a new and useful Warp Stop-Motion, of which the following is a specification.

This invention relates particularly to improvements in warp stop motions of the general type shown in the patent to Regan, No. 1,265,112, dated May 7, 1918.

In this type of warp stop motion, in its preferred form, non-circular controlling or detecting rods are used which extend through openings in the drop wires and which are held from movement when engaged by a fallen drop wire. These controlling rods, when thus held from movement, render a separately actuated knock-off mechanism operative to stop the loom.

It is the object of my present invention to provide a warp stop motion of this type in which a single driven member actuates the detecting rods and also the knock-off mechanism, and it is a further object of my invention to provide such mechanism in a peculiarly simple and effective form.

With these objects in view, my invention consists in certain arrangements and combinations of parts which will be hereinafter described and more particularly pointed out in the appended claims.

A preferred form of my invention is shown in the drawings, in which—

Figure 1 is a side elevation of a loom with my improved stop motion mounted thereon;

Fig. 2 is an enlarged side elevation of the stop motion itself;

Fig. 3 is a rear elevation of the parts shown in Fig. 2;

Figs. 4 and 5 are side elevations similar to Fig. 2, but showing the parts in different positions;

Fig. 6 is a detail perspective view of one of the caps used to hold a detecting rod in position;

Fig. 7 is a detail sectional elevation taken along the line 7—7 in Fig. 2;

Fig. 8 is a detail horizontal section taken along the line 8—8 in Fig. 7, and

Fig. 9 shows a type of drop wire which may be used in my improved stop motion.

Referring to Fig. 1, I have shown a loom side 10 on which one end of the usual bottom or cam shaft 11 is mounted in a bearing 12, said shaft being provided with a cam 13 grooved on its side face to receive a cam roll 14 mounted on one end of a lever 15 pivoted at 16 to the loom side 10. A link 17 is connected at 18 to the opposite end of the lever 15, and the upper end of the link 17 is pivoted at 19 to an arm 20 loosely mounted on a stud 21 fixed in an end member 22 forming part of the stop motion casing or frame 65

The end member 22 is adjustably secured on an L-shaped rod 23, the opposite end thereof being adjustable in a post 24 which in turn is vertically adjustable in a socket 25 secured to the loom side 10. The opposite 70 end of the stop motion is similarly supported and in this way provision is made for vertical, longitudinal, and lateral adjustment thereof.

Detecting rods 26 of non-circular cross 75 section extend through openings 27 (Fig. 9) in drop wires 28, said openings 27 being of sufficient width in their lower portions to permit oscillation of a detector 26 therein, but being narrow in their upper portions so 80 that a fallen drop wire engages the detector and prevents oscillation thereof. The detecting rods 26 are rotatably supported in the end members 22.

A preferred method of supporting the 85 ends of the rods 26 is shown in Figs. 7 and 8 in which a bushing 30 is rotatably mounted in a portion of the frame member 22. A cylindrical hole 31 is drilled part way through the bushing 30, of sufficient size to 90 receive the rod 26. The remaining end portion of the bushing, which is not drilled, is provided with a slot 32 corresponding in width to the thickness of the rod 26 and communicating with the hole 31. The rod 95 26 can therefore be passed freely through the bushing, but is non-rotatable therein.

An arm 33 is rigidly secured to the unslotted end of the bushing 30 for a purpose to be described, and pivoted caps 34 are provided to facilitate insertion and removal of the rods 26 and to prevent accidental displacement thereof.

A detecting rod 26 is provided for each bank of drop wires in the stop motion, and 105 the arms 33 for said rods are connected to

gether at their outer ends by a link 35 (Fig. 2). The right-hand arm 33^a, as viewed in Fig. 2, is formed with an upwardly extending portion 33^b to which one end of a connection 36 is pivotally connected at 37, said connection being U-shaped and the opposite end thereof being slidable in a rocking stud 38 mounted in a forked arm 39 formed integrally with the arm 20 previously described. A collar 40 limits downward movement of the connection 36, and a spring 41 interposed between the rocking stud 38 and a collar 42 yieldingly forces the connection downward to the position shown in Figs. 2, 3 and 4.

Under normal conditions the arm 20 and its extension 39 are rocked continuously by the cam 13 acting through the link 17, and the detector rods 26 are moved alternately from the position shown in Fig. 2 to the position shown in Fig. 4.

A knock-off rod 43 (Fig. 1) has a lost motion connection at its front end to an arm 44 pivoted to the loom side at 45 and connected at 46 to a link 47 through which other parts of the knock-off mechanism of the loom are controlled. The usual shipper lever 48 is also provided for manual control of the knock-off mechanism. The rear end of the rod 43 is connected at 49 (Fig. 2) to a member 50 loosely mounted on the stud 21 and having a latch 51 pivoted thereto at 52, said latch being adapted to engage a tooth or projection 53 on an arm 54 projecting downward from the arm 20 previously described. The latch 51 is also provided with an arm 55 positioned for engagement by a pin 56 mounted on a slide 57 adjustably secured to the left-hand detector arm 33^c.

As the detectors are swung from the position shown in Fig. 2 to that shown in Fig. 4, the arm 55 is raised and the latch 51 is moved out of the path of the moving projection 53. Under these conditions the knock-off mechanism remains undisturbed

and the member 50 rests against the stop 58 on the frame member 22.

Whenever a drop wire falls, however, the oscillating detecting rods 26 and the connected arms 33 are held in the position shown in Fig. 5, with the pin 56 removed from the position in which it depresses the latch 51. The latch 51 is therefore positioned for engagement by the projection 53, and the member 50 is moved thereby to the position shown in Fig. 5, such movement being sufficient to operate the knock-off mechanism through the connecting link 43. During such movement, the spring 41 is compressed as shown in Fig. 5, but is restored to its original length upon the return movement of the link 17.

Having thus described my invention, it will be evident that changes and modifications can be made therein by those skilled in the art without departing from the spirit and scope thereof as set forth in the claims, and I do not wish to be otherwise limited to the details herein disclosed, but what I claim is—

1. A warp stop motion having, in combination, a plurality of drop wires arranged in parallel banks, oscillating detecting rods for said drop wires, arms and linkage connecting said rods to oscillate together, actuating means for said rods including a yielding connection, knock-off mechanism, and a connection between said actuating means and said mechanism including an engaging device normally in engaging position but movable from engaging position on every unobstructed oscillation of said rods.

2. In a warp stop motion, a yielding connection comprising a U-shaped rod having a shorter portion terminating in an eye, and having a longer straight portion upon which a compression spring is adjustably secured.

In testimony whereof I have hereunto affixed my signature.

ELBRIDGE R. HOLMES.
